FIG. 6.

Inventor

S. E. Douglass,

By *S. E. Douglass*

Attorney

UNITED STATES PATENT OFFICE.

SAMUEL E. DOUGLASS, OF RALEIGH, NORTH CAROLINA.

SPARK ARRESTER.

Application filed April 10, 1922. Serial No. 551,096.

To all whom it may concern:

Be it known that I, SAMUEL E. DOUGLASS, a citizen of the United States, residing at Raleigh, in the county of Wake and State 5 of North Carolina, have invented certain new and useful Improvements in Spark Arresters; and I do hereby declare the following to be a full, clear, and exact description of the invention, such as will enable others skilled in the art to which it 10 pertains to make and use the same.

The invention has relation to the type of spark arresters designed more particularly for locomotives and contemplates the provision of means for catching and retaining the sparks until the same may be safely disposed of without causing fire or annoyance.

In accordance with the present invention, a baffle or deflector is disposed within the 20 flared delivery end of the smoke stack and branches and terminates in conduits which lead to boxes in which the sparks collect and cool and from which the accumulation is discharged as required.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the 35 invention.

Referring to the accompanying drawings forming a part of the application,

Figure 1 is an elevation of portion of a locomotive provided with a spark arrester 40 embodying the invention,

Figure 2 is a transverse section of the body portion of the locomotive on the line 2-2 of Figure 1, showing the parts on a larger scale, one of the boxes for receiving 45 the sparks being in full lines.

Figure 3 is a sectional detail on the line 3-3 of Figure 2,

Figure 4 is a horizontal section on the line 4-4 of Figure 2,

Figure 5 is a detail section on the line 5-5 of Figure 2, and

Figure 6 is a detail elevational view of the spark arresting baffle or deflector.

Corresponding and like parts are re-

ferred to in the following description and 55 designated in the several views of the drawings by like reference characters.

The numeral 1 designates the body of a locomotive of any ordinary make or design and 2 the smoke stack which terminates in 60 the flared end 3. At each side of the body 1 is located a box 4 which is adapted to receive the sparks or cinders escaping from the stack. The bottom and rear wall of the box 4 slope so as to readily discharge the 65 contents through the opening formed in the front of the box and which is normally closed by means of a door 5. A pipe 6 leads upwardly from each of the boxes 4 and conveys the sparks and cinders thereto. 70

The spark arresting baffle or deflector is arranged within the smoke stack and comprises a vertically disposed plate 7 and upwardly diverging plates 8 which terminate at their upper ends in elbows 9 which are 75 coupled to the pipe 6. The vertical plate 7 is centrally disposed within the lower portion of the stack 2 and is held in place by means of bolts 10, or like fastening means. The diverging plates 8 are provided with a 80 plurality of relatively small openings for the escape of smoke and gases, but which prevent the passage of sparks and cinders. The openings in the plate 8 may be of any form and arrangement found most advantageous. 85 The upper ends of the plates 8 have their opposite side portions curved inwardly and otherwise shaped to provide the elbows 9 which catch and direct the sparks and cinders into the pipe 6. Inasmuch as the upper 90 portions of the elbows 9 are subjected to abrasive action and wear, they are made thicker to sustain such wear.

In the practical operation of the invention, the smoke and gases laden with sparks and cinders enter the stack 2 and are divided by the vertical portion 7 of the deflector and passing along the diverging plate 8 are subjected to a lateral deflection which effects a separation of the sparks and cinders from the smoke and gases, the latter passing through the openings of the plate 8 and the sparks and cinders being arrested and directed into the elbows 9 and from thence into the pipe 6 by which they are conveyed to the boxes 4, in which they accumulate to be discharged therefrom at intervals by opening the door 5. 100 105

What is claimed is:

A spark arrester comprising, in combination with a smoke stack, a vertically disposed flat dividing plate arranged within 5 and extending diametrically of the stack and having its side edges engaging the inner walls of the stack, a pair of flat deflecting plates extending upwardly in diverging relation from the upper edge of the dividing 10 plate and having their side edges contacting with the inner surface of the stack, the deflecting plates being perforated and terminating at their upper ends in return elbows which overlie and engage the upper edge of 15 the stack and which are of a length equal to the width of the deflecting plates, the inner end of the return elbow having openings coextensive in length with the width of the

deflecting plates and having their end walls curved to engage the inner surface of the 20 stack and the outer ends of the elbows terminating in reduced nipples, discharge pipe connected to said nipples, and means passing through the dividing plate and the smoke 25 stack, said means in addition to the engagement of the deflecting plates and elbows with the stack preventing the spark arrester from having any movement with respect to the stack.

In testimony whereof I affix my signature 30 in presence of two witnesses.

SAMUEL E. DOUGLASS.

Witnesses:

CLYDE A. DOUGLASS,
J. R. LOWERY.
